CHICK BOX

Louis A. Shoemaker, Carleton, Mich.

Application October 5, 1936, Serial No. 103,979

19 Claims. (Cl. 229—6)

This invention relates to boxes for shipping baby chicks, and more particularly to those made of corrugated fiberboard, or similar sheet material.

Generally stated, the object of the invention is to provide a novel and improved construction whereby a satisfactory box of this kind is provided, of such character that no staples, or nails, or glue, or other fastening means, are necessary in the setting up and securing together of the blanks of which the box is composed.

It is also an object to provide certain details of construction and combinations tending to increase the general efficiency and desirability of a chick box of this particular character.

To the foregoing and other useful ends, the invention consists in matters hereinafter set forth and claimed and shown in the accompanying drawings, in which—

Fig. 1 is a perspective of a chick box embodying the principles of the invention.

Fig. 2 is a longitudinal section thereof on line 2—2 in Fig. 1.

Fig. 3 is a fragmentary perspective view of one corner portion of the box.

Figs. 4 and 5 are large detail fragmentary sectional views of said corner portion.

Fig. 6 is an enlarged fragmentary perspective view of the handle portion of the box.

Fig. 7 is a detail section on line 7—7 in Fig. 6.

Fig. 8 is a similar view, showing the parts in different positions.

Fig. 9 is a plan view of the blank from which the body of the box is made.

Fig. 10 is a plan view of the blank from which the handle and the transverse partition are formed.

Fig. 11 is a plan view of the blank from which the cover is made.

Fig. 12 is a side elevation of the longitudinal partition of the box.

Figs. 13 and 14 are fragmentary perspective views showing different forms of the invention.

Fig. 15 is a detail section on line 15—15 in Fig. 14.

Fig. 16 is a similar view, showing the parts in different positions.

Fig. 17 is a transverse section on line 17—17 in Fig. 13.

Figs. 18, 19, 20 and 21 are views of blanks, showing different forms of the invention.

As thus illustrated, and referring to Figs. 1 to 12 of the drawings, the invention comprises a main box body blank, as shown in Fig. 9 of the drawings, having a rectangular bottom wall sec-

tion 1, end wall sections 2, and side wall sections 3, all flexibly connected together to fold along the lines 4 and 5, to form a box body with a bottom and upright side and end walls. The sections 2 have tongues 6, and the ends of the sections 3 have tongues 7, as shown in Fig. 9 of the drawings. The slots 8 in the sections 2 are formed to receive the tongues 7, and also the tongues 6, after the latter are inserted through the slots 9, as shown more clearly in Figs. 1, 3, 4 10 and 5, thus forming a very strong corner construction for the body of the box.

The transverse partition of the box is formed by the blank shown in Fig. 10 of the drawings, comprising two upright sections 10 connected together by a handle section 11, the sections 10 having end tongues 12 for insertion in the slots 13 of the side walls 3, when the box is assembled as shown in Fig. 1 of the drawings. The sections 10 also have notches 14, as shown. When the blank shown in Fig. 10 is properly folded and assembled with the box body, the sections 10 are more or less upright, and converge downwardly from the handle section 11, as shown in Fig. 2 of the drawings.

The longitudinal partition blank 15, as shown in Fig. 12 of the drawings, has a straight lower edge and a depressed upper edge, with a notch 16 in the middle of the depression. The ends of this wall have tongues 17 for insertion in the slots 18 of the end walls 2, when the blanks are assembled, as shown in Fig. 1 of the drawings.

The cover blank is substantially rectangular in form, as shown in Fig. 11 of the drawings, and has the two cover sections 19 flexibly connected together by fold lines 20 and 21, and separated by a transverse slot 22 at the middle of the blank. The sections 19 have their side edges provided with tongues 23, which tongues are inserted downwardly inside of the flap corners 24, 40 as shown more clearly in Fig. 1 of the drawings. Thus, the middle portion of the cover is depressed transversely and the handle, formed by section 11 and the upper portions of the sections 10, extends upwardly through the slot 22, a distance 45 above the upper surface of the cover, at the middle of the top of the box, as shown in Figs. 1, 2, 6, 7 and 8 of the drawings. The hollow handle-like portion, because of the holes in the two flat walls 10, serves also as a ventilator for the top of the 50 box.

In this way, the four blanks from which the box is made are set up and assembled together without the necessity of using any staples, or nails, or glue, or pins, or any other fastening 55

means. Preferably, corrugated fiberboard is used as the material from which to make the blanks, thus insuring lightness with strength for the box.

As will be observed by looking at the drawings, 5 the different walls of the box, with the exception of the bottom wall, may be provided with ventilating openings, shown as round holes in the drawings, to any extent desired for the box, thereby to insure proper ventilation for the 10 interior of the box.

As shown in Figs. 13 to 21 inclusive, the construction is similar to that previously described, but in this case the longitudinal partition 25 is double, comprising two side walls 26 that converge downwardly, and top walls 27, with the opening 28 in the middle of the blank, as shown in Fig. 21 of the drawings. The walls 10 have openings 29 for the tongues 30 on the two cover sections 31, as shown in Figs. 15 and 16 of the 15 drawings, and as indicated in Fig. 14 of the drawings. The tongues 32 on the ends of the longitudinal partition extend through the slots 33 in the end walls of the box body, as shown in Fig. 13 of the drawings. As shown in Fig. 19, 20 the blank for the transverse partition and the handle is substantially like that shown in Fig. 10 of the drawings, except that in this case notches 34 are provided, having their inner ends provided with tongues 35 for insertion between 25 the upper edges of the notches 36 of the longitudinal partition. Thus, with this modification of construction previously described, the box has a folded double-wall longitudinal partition, as well as a folded double-wall transverse partition. 30

Thus, in each form of the invention, there is 35 a strong and effective cover and partition construction, that provides the box with a rugged and comfortable handle at the middle and top of the box, and with two upwardly opening covers and a transverse partition and a longitudinal partition combined therewith. Also, in each form of the invention, the corner construction of the body of the box is strong and effective, and the tongue and slot connections between 40 the different blanks are of such character that the box is not liable to come apart, notwithstanding that staples and nails and glue and other fastening means are not employed, and are not necessary.

With the construction shown and described, 45 the section 11 of the handle is flush with the tops of the cover sections 19, as shown in Fig. 2 of the drawings, so that one box of the kind shown and described can stand on another and the boxes can be stacked one on top of another for storage or shipment.

It is obvious, therefore, that in each form of 50 the invention the box has not only a double transverse partition, but also a double longitudinal partition, with apertured walls, thus forming flues for ventilation purposes. Obviously, in addition, the raised portion 11 of the double transverse partition provides a dove-tailed means for firmly gripping the cover of the box in order 55 that the cover may be secured in the center as well as at the four corners thereof. In addition, it will be seen that the space in each double partition communicates with the hollow handle of the box, thus further insuring effective ventilation. 60

Thus it will be seen that the elevated horizontal sections 19 of the cover construction extend over the edges of the four side walls, and that a box body corner construction is provided 65 for holding the two covers in closed position, in

the manner shown and described. Also, this corner construction serves to simplify and facilitate the setting up of the box, by folding the blanks as shown and described, and eliminates the necessity of any fastening devices such as staples 5 or similar things, the three blanks being sufficient in themselves to hold them rigidly in folded and interengaging position.

Obviously, by inserting both tongues 6 and 7 through the slot 8, the flat portion 24 is held 10 very tightly against the side of the box, and in this way the flaps 23 are gripped very tightly, and thus the said tongues and flaps co-operate effectively to hold the cover in closed position.

What I claim as my invention is: 15

1. A chick box comprising a body and two upwardly opening integrally connected top covers therefor, and a handle section formed from a single blank separate from the covers and disposed between the two covers and having downwardly converging flat walls extending to the bottom of the box and forming a transverse hollow partition for the interior of the box, with the integral hollow upper end of said partition forming the handle at the middle of the top of the 25 box, which handle is open at each end and serves as a ventilator.

2. A structure as specified in claim 1, said covers having portions that slope downwardly toward the handle so that the latter projects 30 above the middle portion of the top of the box.

3. A structure as specified in claim 1, said handle section having openings immediately below the handle proper, and said covers having tongues for insertion in said openings, when the covers 35 are closed.

4. A structure as specified in claim 1, said handle section having a top portion forming a hollow handle, the top of the latter being substantially flush with the tops of the two covers. 40

5. A structure as specified in claim 1, said partition having a pair of tongues at each end thereof, the side walls of the box having slots for said tongues, preventing upward displacement of said handle. 45

6. A structure as specified in claim 1, said partition having end portions underlying the top of the box and having its lower edge formed with a middle notch, and a longitudinal partition having its middle portion formed to interlock with 50 the said notch.

7. A structure as specified in claim 1, said handle being of less length than the width of the box, and the two covers being integrally joined together by flat sections disposed at the opposite 55 ends of the handle, with the latter extending a distance above the two flat sections, which latter are in the same horizontal plane, so that the top of the handle is substantially flush with the top portion of the cover.

8. A structure as specified in claim 1, said partition having downwardly converging flat walls flexibly connected together at their upper edges, above the adjacent portions of the covers. 60

9. A structure as specified in claim 1, said partition having downwardly converging flat walls flexibly connected together at their upper edges, above the adjacent portions of the covers, with tongues on the ends of said downwardly converging walls and slots in the side walls of the 70 box to receive said tongues.

10. A chick box provided with a hollow longitudinal ventilating partition therein, with its lower edge at the bottom of the box, said partition comprising two downwardly converging flat 75

walls flexibly connected together at their upper edges, under the top of the box, the top of the partition being open at the middle portion thereof, and means at the ends of said downwardly converging walls to hold the partition in place.

11. A chick box provided with a separately formed longitudinal partition therein, said partition having tongues at the ends thereof, and the end walls of the box having slots to receive 10 said tongues, each tongue being disposed a distance below the upper edge of the partition, cover for the box, and a separate handle section forming a transverse hollow partition extending at right angles to and interengaging with the middle portion of said longitudinal partition, forming 15 a hollow handle and ventilator projecting through and above the middle portion of the cover.

12. A chick box comprising a body and two upwardly opening top covers therefor, and a handle section disposed between the two covers and having downwardly converging walls forming a transverse partition for the interior of the box, said covers having portions that slope downwardly toward the handle so that the latter projects above the middle portion of the top of the box.

13. A chick box comprising a body and two upwardly opening top covers therefor, and a handle section disposed between the two covers and having downwardly converging walls forming a transverse partition for the interior of the box, said handle section having openings immediately below the handle proper, and said covers having tongues for insertion in said openings, when the covers are closed.

14. A box of the type described, having a rectangular bottom and four side walls, and a cover construction comprising a single blank formed 40 to provide a depressed middle portion and elevated horizontal articulated end portions, the latter forming the top of the box and extending over upper edges of the four side walls, forming two upwardly opening cover sections, fastening means to hold said middle portion in fixed posi-

tion, and means at the four corners of the box to retain said cover sections in closed position, disposed between said corners and the points of articulation of said cover end portions, so that the latter can be raised and closed independently 5 of each other.

15. A structure as specified in claim 14, said fastening means comprising a hollow partition having a portion extending inwardly through said middle portion, with means on the ends of said 10 partition to extend through two side walls.

16. A structure as specified in claim 14, said retaining means comprising flaps on the ends of two opposite side walls, flush with the tops of these side walls, having portions inserted inwardly through the other two side walls, and then outwardly through the first side walls, said 15 articulated horizontal cover sections having end portions inserted downwardly between said flaps and the outer surfaces of said other side walls. 20

17. A structure as specified in claim 14, said retaining means comprising flaps on the ends of two opposite side walls, flush with the tops of these side walls, having portions inserted inwardly through the other two side walls, and 25 then outwardly through the first side walls, said articulated horizontal cover sections having end portions inserted downwardly between said flaps and the outer surfaces of said other side walls, and the latter having end portions also extending 30 through said first side walls.

18. A structure as specified in claim 14, said cover construction comprising a single blank with a transverse slot in said middle portion, and a single perforate blank forming a hollow transverse partition extending upwardly through said slot, forming a ventilator and handle, with the top of the latter flush with said cover end portions. 35

19. A structure as specified in claim 14, with 40 a hollow ventilator and handle extending upwardly through said middle portion, flush with said horizontal cover end portions.

LOUIS A. SHOEMAKER.
